MUCKING MACHINE

Anthony R. Biedess, Chicago, Ill., assignor to
 Goodman Manufacturing Company, Chicago,
 Ill., a corporation of Illinois

Application March 3, 1950, Serial No. 147,490

5 Claims. (Cl. 214—90)

1

This invention relates to improvements in mucking machines of the kind employing a dipper and boom arranged for horizontal and vertical swinging movement at the front end of the machine, as broadly disclosed in Mosier Patent #1,514,008.

Among the objects of the present invention is to provide an improved arrangement of drive connections for controlling the movement of the dipper and boom.

A further object is to provide an improved construction and arrangement of power connections for the scoop actuating devices which permit an increased width and corresponding added carrying capacity of the discharge conveyor.

A still further object is to provide a cushioning support for the entire receiving end of the discharge conveyor to where the material is deposited from the scoop upon the conveyor belt.

Still another object is to provide an improved means for adjusting the slack in the conveyor belt drive chain.

These and other objects of the invention will appear from time to time as the following description proceeds.

The invention may best be understood by reference to the accompanying drawings, in which:

Figure 1 is a side view of a mucking machine illustrating one embodiment of the invention;

Figure 2 is a top plan view of the machine shown in Figure 1;

Figure 3 is an enlarged fragmentary detailed section taken generally on line 3—3 of Figure 2;

Figure 4 is a fragmentary detailed side view in part section taken generally on line 4—4 of Figure 2 and shown to the same scale as Figure 3;

Figure 5 is a section taken on line 5—5 of Figure 4;

Figure 6 is a perspective view of a floating frame on which the front end of the conveyor belt is mounted;

Figure 7 is a sectional view taken generally along line 7—7 of Figure 4;

Figure 8 is a sectional view taken along line 8—8 of Figure 4;

Figure 9 is a fragmentary detailed view from the exterior of the front end of the main frame taken along line 9—9 of Figure 7;

Figure 10 is a detailed section taken along line 10—10 of Figure 4; and

Figure 11 is a detailed section taken along line 11—11 of Figure 10.

Referring now to details of the embodiment of my invention illustrated in the drawings, the

2

mucking machine consists essentially of the main frame 10 having spaced side plates 11, 11 connected by a rear bumper plate 12 and a front cross member 13. A dipper 14 is pivotally connected on a horizontal axis to a boom 15, which boom in turn is pivoted for vertical and lateral swinging movement with respect to a support 16 mounted at the front end of the main frame 10. The dipper and boom shown herein are of conventional form and arrangement heretofore employed in mucking machines. Their movement is controlled, as usual, by a pair of chains 17, 17 connected at their front ends to opposite sides of the dipper and having their rear ends wound on drums 18, 18 carried on a transverse shaft 19 extending the full width of the machine and supported at opposite ends in standards 20 and 21 extending above the side plates 11, 11 of the main frame. The chain drums 18, 18 are independently controlled for winding in either one or both of the chains 17, 17 during the operation of the machine, as will hereinafter more fully be described.

The machine is also equipped with a discharge conveyor, indicated generally at 24, for handling the material which is deposited by the dipper onto the boom 15 and from thence is discharged by gravity upon the front end of the discharge conveyor when the dipper and boom are elevated to an upwardly inclined position. The discharge conveyor includes a pair of side frame members 25, 25 which are fixed to the side plates 11, 11 near the front end of the main frame and extend upwardly and rearwardly therefrom to a relatively high level at the rear end of the frame. From thence, the side frame members 24 are continued at a decreased upward angle to form a rearwardly overhanging discharge boom, indicated at 26 at the rear end of the machine. The general structure and arrangement of the discharge conveyor, including the side plates 25 and the overhanging discharge boom 26, is similar to that heretofore employed in machines of this character so details thereof need not be further described herein, excepting to refer to an endless belt 27 which moves over a bottom plate 29 fixed between the side members 25 and is trained at its rear end over an idler pulley 28 mounted for longitudinal adjustment as usual at the rear end of the overhanging boom 26 of the discharge conveyor.

Referring now more particularly to certain novel features of the present invention, the front end of the conveyor belt 27 is trained over a drive pulley 30 mounted on a shaft 31 having its op-

posite ends journalled in a floating frame indicated generally at 32. Said floating frame includes two upright side plates 33 and 34 cross-connected by a bottom plate 35, over and along which the belt 27 is supported as it moves rearwardly from the drive pulley 30.

As will be seen in Figure 3, the floating frame 32 is pivotally mounted at its rear end on a transverse pivot pin 36 having its outer ends passing through apertures 37 and 38 in the side plates 33, 34 and having its outer ends suitably journalled in the side plates 11, 11 (see Figure 8). The upper surface of the bottom plate 35 of the floating frame is disposed in a plane above the pivot pin 36 on which the said floating frame swings. When said frame is in its normal operating position, as shown in Figure 3, said bottom plate is arranged substantially in alignment with the bottom plate 29 fixed to the side frame members 25 of the discharge conveyor so that the conveyor belt 27 may pass directly from supporting engagement with the movable bottom plate 35 of the floating frame to the fixed bottom plate 28 of the discharge conveyor, where said belt passes over the pivot pin 36. The front edge of the movable bottom plate 35 terminates closely adjacent and substantially tangential to the drive pulley 30 at the front end of the floating frame 32.

The lower or return reach of the belt 27 may be trained over an idler roller 42 having its opposite ends rotatably mounted on the side plates 33, 34 below the bottom plate 35. From thence, the return reach of the belt may be passed upwardly and rearwardly beneath the pivot pin 36 and over one or more idler rollers 43 having their ends rotatably mounted on the conveyor side frame members 25 toward the rear end of the discharge conveyor.

As will be seen in Figures 6 and 7, the floating frame 32 has two laterally extending angle members 45, 46 connected to the outer sides of the walls 33 and 34 respectively. These angle members project outwardly through upright slots 47 and 48, respectively, formed in the side plates 11, 11 of the main frame, and rest on the upper ends of coil springs 49 and 50 respectively. The lower ends of said springs rest on washers 51, 52 connected by bolts 53, 54 passing upwardly through the respective springs 49 and 50 and connected at their upper ends to cross bars 55 and 56 fixed to the respective side plates 11, 11. By means of this yieldable suspension means, the front end of the floating frame 32 is supported for limited rocking movement about its pivot pin 36 to provide a cushioning effect for the entire front end of the conveyor structure, including belt 27 and the floating bottom plate 35 and drive pulley 30, when material is deposited on the belt from the boom at the front end of the machine.

Referring now to the drive mechanism for the several operative devices on the machine, a motor which may be of the electric type indicated at 60, is suitably mounted near the rear end of the main frame and has a pinion 61 drivably engaged with gear 62 mounted on a cross shaft 64. The motor 60 and cross shaft 64 are located below the inclined discharge conveyor 24 but, in the form shown, a part of the drive, consisting of the pinion 61 and gear 62, is disposed toward one side of said discharge conveyor, at the left-hand side of the machine, as shown in Figure 2. The cross shaft 64 has a sprocket 65 connected as by chain 66 and sprocket 67 to a second cross shaft 68 disposed forwardly and below the cross shaft

64 with said chain and sprockets below the level of the discharge conveyor, as shown in Figures 3 and 4.

From the cross shaft 68, drive connections are provided, as is more or less conventional in machines of this type, to the front and rear track wheels 70 and 71 of the main frame, as for instance through a sprocket 72 fixed on the cross shaft 68, chain 73 and a sprocket 74 fixed on a cross shaft 75 between the front and rear wheels. A pair of planetary drive mechanisms 76 and 77 are mounted on the cross shaft 75 connected as by chains 78 and 79 to the front and rear wheels for driving the latter in forward or backward directions, as desired. The planetary mechanisms and their drive connections to the wheels may be similar to the kind disclosed in the Mosier Patent #1,514,008, so further details thereof need not be described herein. It will be noted that all the wheel driving connections, including the planetary mechanisms 76 and 77, are located below the discharge conveyor adjacent the center of the machine.

Referring now to the drive connections for the chain drums 18, 18, previously described as being carried on the transverse shaft 19 at the front end of the machine above the discharge conveyor, a chain sprocket 80 is mounted near the left end of the cross shaft 68, beyond the left side of the discharge conveyor and its adjacent side frame member 25 as shown in Figure 2. A chain 81 extends from the sprocket 80 upwardly and forwardly over an idler sprocket 82 on cross shaft 83 fixed between the standards 20 and 21 and, from thence, to a chain sprocket 84 fixed to the transverse shaft 19. From the sprocket 84, the chain 81 passes downwardly and rearwardly about an idler sprocket 85 on shaft 86 and, from thence, downwardly and forwardly about sprocket 87 fixed on the conveyor belt drive shaft 31. From thence, the chain 81 continues upwardly and rearwardly about an idler sprocket 88 on stub shaft 89 carried on a block 90 which is guided for vertical adjustment in an upright slot 91 formed in the side wall 34 of the floating frame 32. From thence, the chain extends downwardly and rearwardly to the sprocket 80 on cross shaft 68.

The block 90, carrying idler sprocket 88, may be fixed in various positions of adjustment by a nut 90a engaging the inner face of the side wall 34 (see Figures 10 and 11).

The sprocket 84 drives transverse shaft 19 continuously in one direction while the drive chain 81 is being driven. A pair of planetary gear devices 95 and 96 are mounted on the shaft 19, these planetary gear devices being operable to drive the chain drums 18, 18 either simultaneously or independently of each other under the control of brake bands 97 and 98 on cross shaft 83. The planetary gear devices and their brake controlling means may be of the same type broadly disclosed in the Mosier Patent #1,514,008, so their details of construction need not be further described herein.

A flanged projection 99 may be provided along a forward inclined portion of the side wall 34 of floating frame 32 to form a guard for the chain 81 as it passes between sprockets 85 and 87.

The use and operation of the machine above described is as follows:

The machine is propelled along the track by its drive motor 60 operating through the planetaries 76 and 77 in the conventional manner. While digging, the dipper 14 and boom 15 are

lowered to a position substantially as shown in Figure 1, and the machine is propelled bodily forwardly to gather material in the dipper. Material is unloaded from the dipper to the loading boom and, from thence, onto the front end of the discharge conveyor 24 by operating the planetaries 95 and 96 in the customary manner to wind the chains 17, 17 on the drums 18, 18, and elevate the dipper and boom into inclined position to discharge the material upon the front end of the conveyor 24.

It will be observed that, by reason of the pivotal mounting of the floating frame or belt-supporting section 32 with its front end yieldably supported on springs 49 and 50, the entire front end of the conveyor belt 27 with its drive roller 30 are yieldably supported relative to the main frame and its fixed belt-supporting section, so as to cushion any effects of any excessive weight of material discharged from the boom onto the conveyor.

It will be observed further that the chain drive connections extending from the cross shaft 68 below the discharge conveyor to the cross shaft 19, on which the chain drum operating planetaries 95 and 96 are mounted, consists of a single chain 81 moving in an orbital path disposed to one side of the discharge conveyor 24, and that this chain 81 also provides drive connection to the belt drive roller 30 mounted at the front end of the floating frame 32. By arranging all the chain drive connections to the sprocket shaft 19 and the conveyor roller 30 along one side of the discharge conveyor in the manner just described, I find it possible to increase the effective width of the conveyor belt 27 by several inches as compared with conventional chain drive connections heretofore employed in machines of this kind wherein a part of the chain driving connections are disposed at one side of the discharge conveyor and another part of said connections are disposed at the opposite side of the conveyor.

It will be observed further that, by mounting the adjustable take-up idler sprocket 88 on the floating frame 32 for movement with the latter, in the manner disclosed herein, drive chain 81 may be automatically maintained at the proper tension to compensate for any vertical yielding movement of the floating frame 32, including the belt driving roller 30 at the front end of said floating frame.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. In a mucking machine, a main frame having a dipper pivotally mounted for vertical dumping movement at its front end, hoisting means for said dipper on the front end of said frame, an elevating conveyor including an endless belt mounted on said frame and arranged to receive material from said dipper at a relatively low level at the front of said frame and to carry it for discharge at a relatively high level at the rear of said frame, said conveyor having a belt-supporting section at its front end mounted for yielding vertical movement relative to said frame and having a drive pulley for said belt journalled at the front end thereof, power means on said frame below said conveyor, and drive connections from said power means to said belt drive pulley

including a drive chain moving in an orbital path in a vertical plane at one side of said conveyor, and extending generally in alignment with said front belt supporting section.

5 2. In a mucking machine, a main frame having a dipper pivotally mounted for vertical dumping movement at its front end, hoisting means for said dipper on the front end of said frame, an elevating conveyor including an endless belt mounted on said frame and arranged to receive material from said dipper at a relatively low level at the front of said frame and to carry it for discharge at a relatively high level at the rear of said frame, said elevating conveyor having a rear belt-supporting section fixed on said frame and a front belt-supporting section pivotally mounted on a transverse axis adjacent the front end of said fixed section for yieldable swinging movement relative to the latter, said front section having a drive pulley for said belt journalled at the front end thereof, power means on said frame below said conveyor, and drive connections from said power means to said belt drive pulley including a drive chain moving in an orbital path in a vertical plane at one side of said conveyor, and extending generally in alignment with said front belt supporting section.

10 3. In a mucking machine, a main frame having a dipper pivotally mounted for vertical dumping movement at its front end, hoisting means for said dipper on the front end of said frame, an elevating conveyor including an endless belt mounted on said frame and arranged to receive material from said dipper at a relatively low level at the front of said frame and to carry it for discharge at a relatively high level at the rear of said frame, said elevating conveyor having a rear belt-supporting section fixed on said frame and a front belt-supporting section pivotally mounted on a transverse axis adjacent the front end of said fixed section for yieldable swinging movement relative to the latter, said front section having a drive pulley for said belt journalled at the front end thereof, power means on said frame below said conveyor, and drive connections from said power means to said belt drive pulley including a single drive chain moving in an orbital path in a vertical plane at one side of said conveyor, and having a portion thereof extending generally in alignment with said front belt supporting section.

15 4. In a mucking machine, a main frame having a dipper pivotally mounted for vertical dumping movement at its front end, hoisting means for said dipper on the front end of said frame, an elevating conveyor including an endless belt mounted on said frame and arranged to receive material from said dipper at a relatively low level at the front of said frame and to carry it for discharge at a relatively high level at the rear of said frame, said elevating conveyor having a rear belt-supporting section fixed on said frame and a front belt-supporting section pivotally mounted on a transverse axis adjacent the front end of said fixed section for yieldable swinging movement, said front section having a drive pulley for said belt journalled at the front end thereof, power means on said frame and drive connections from said power means to said belt drive pulley including a drive chain, said front section having an idler pulley mounted thereon over which said drive chain is trained to compensate for variations in tension of said drive chain during swinging movement of said front section.

5. In a mucking machine, a main frame having upright side plates and a dipper pivotally mounted for vertical dumping movement at the front end, an elevating conveyor including an endless belt mounted on said frame and arranged to receive material from said dipper at a relatively low level at the front of said frame and to carry it for discharge at a relatively high level at the rear of said frame, said elevating conveyor having a rear belt-supporting section fixed on said frame and a front belt-supporting section pivotally mounted on the transverse axis adjacent the front end of said fixed section, said front section having a pair of laterally extending angle members fixed thereon, the side plates of the main frame having open slots through which said angle members project, and adjustable spring means supporting said angle members on said side plates to afford yieldable vertical move-

ment of said front supporting section relative to said main frame.
